REFRIGERATOR CONTAINER OR THE LIKE

Cyril J. Yates, Henderson, Ky., assignor to Tri-State Plastic Molding Co., Henderson, Ky., a limited partnership

Application June 19, 1948, Serial No. 147,080

Term of patent 14 years

(Cl. D44—1)

To all whom it may concern:

Be it known that I, Cyril J. Yates, a citizen of the United States and a resident of Henderson, Kentucky, have invented a new, original, and ornamental Design for a Refrigerator Container or the Like, of which the following is a specification, reference being had to the accompanying drawing, forming part hereof, in which:

Fig. 1 is a plan view of a refrigerator container or the like embodying my new design.

Fig. 2 is a front elevation of the same with the two parts thereof separated.

Fig. 3 is an end elevation of the same.

Fig. 4 is a bottom view of the same.

Fig. 5 is an end elevation in section taken along lines 5—5 in Fig. 1.

I claim:

The ornamental design for a refrigerator container or the like, as shown.

CYRIL J. YATES.
